UNITED STATES PATENT OFFICE.

JAMES P. CASSIDY, OF NEW HAVEN, CONNECTICUT, ASSIGNOR TO JOHN W. LADD, OF NEW HAVEN, CONNECTICUT.

LOCKING DEVICE FOR ELECTRIC-LIGHT BULBS.

1,360,266.

Specification of Letters Patent. Patented Nov. 30, 1920.

Application filed April 7, 1919. Serial No. 288,029.

To all whom it may concern:

Be it known that I, JAMES P. CASSIDY, citizen of the United States, residing at New Haven, in the county of New Haven and State of Connecticut, have invented certain new and useful Improvements in Locking Devices for Electric-Light Bulbs; and I do hereby declare the following to be a full, clear, and exact description of the invention, such as will enable others skilled in the art to which it appertains, to make and use the same.

My invention relates to a locking device to prevent surreptitious removal of electric light bulbs from their sockets, and it consists in certain details of construction to be more fully set forth in the following specification.

Referring to the accompanying drawings 20 wherein certain figures and letters of reference indicate like parts throughout the several views:

Figure 1 represents a detail view of the locking device;

Fig. 2 is a broken view of lamp casing partly in section showing the lock mounted on the threaded socket shell in the porcelain base, or socket;

Fig. 3 is an enlarged broken view partly 30 in section of the lamp casing, and the glass bulb showing the latter seated around the threaded shell of the base or socket with the lock in operative position;

Fig. 4 is an enlarged broken view partly 35 in section of the lower part of the locking device, and

Fig. 5 is a broken view of an ordinary glass bulb with its threaded shell.

The locking device consists of the coil 1 40 carrying at its lower end the metal strip 2 to serve as an anchor or locking means in connection with the shell or casing 3, as follows: After the casing is in place, the coils of the lock are engaged with the metal 45 threaded shell 4, Fig. 2, until the edge of anchor 2 rests on the shoulder 6 of the socket 7. It will be understood that the anchor wedges between the shoulder 6 and the lower thread of the shell 4. Also it is 50 frictionally engaged by the said shell 4 and casing 3. After the coils are in place on the shell 4, the said shell is slipped into the casing 3 from the bottom or larger end, and thus the anchor is securely locked and

wedged in place, so that it will be impossible to move the same without dismantling the complete socket. This will leave several coils of the lock projecting above the threaded socket shell of the socket as shown. The lamp shell 8 is then screwed into the threaded socket shell of the socket in the usual manner.

In bringing the shell 8 into engagement with the socket, the exposed or projecting coils of the lock will be compressed, and as 55 the shell is being screwed into the socket these exposed coils will also engage the threaded grooves 9 of the shell to form the gripping coils *a*, Fig. 3, when the lamp bulb is fully seated.

As shown in Figs. 1 and 4, the anchor 2 is secured by one end to the end of the lower coil of the lock with its free end projecting outside of the coil. When the coil of the spiral lock is being embraced by the casing 70 3 the free end of the anchor 2 is forced inward by the frictional contact of the casing therewith, and when the anchor rests on the shoulder 6 of the socket, this wedging and friction as before described is sufficient to 75 prevent further travel of the lower end of the spiral coil of the lock while the lamp shell is being screwed into the socket in the direction of arrow *b*, Fig. 3. This inward movement will tend to expand or open the 80 exposed coils *a*, and when the electric bulb 10 is seated, the reactionary grip of the coils *a* against the shell 8 will effectually prevent 85 a reverse movement of the bulb. The only way to release the grip of these upper coils 90 is by simply lifting the free end 11 and thus break the grip of the coils when the bulb can be readily unscrewed. As this free end 95 is entirely hidden within the embrace of the casing 3, it can only be reached by breaking the bulb, which bulb will then have no commercial value. When the lamp is burned out, the bulb will then be broken and its shell easily removed in the manner before mentioned.

The length of the anchor 2 is immaterial 100 so long as it serves the purpose for which it is intended.

It will be understood that all parts of the electric lamp shown are old and form no 105 part of my invention, which consists only in the application of my improved lock thereto and for the purpose above set forth.

Having thus described my invention, what I claim is:—

- 1: In combination with an electric lamp socket comprising an insulating base, and a threaded contact shell fitting snugly with an outer casing, a lock comprising a metal coil and a locking piece secured to the lower end of the coil, said coil engaging the outer surface of the shell, and said locking piece projecting adjacent to the lower inner end of the shell so as to be securely locked and wedged between the base and the lower thread of the shell, said coil having a part which projects above the open end of the socket and which engages the threaded lamp base when the latter is inserted in the socket.
2. In combination with an electric lamp

socket comprising an insulating base, and a threaded contact shell fitting snugly with an outer casing, a lock comprising a metal coil and a locking piece composed of a curved member secured at one end to the lower end of the coil and having its opposite end free, said coil engaging the outer surface of the shell, and said locking piece projecting adjacent to the lower inner end of the shell so as to be securely locked and wedged between the base and the lower thread of the shell, said coil having a part which projects above the open end of the socket and which engages the threaded lamp base when the latter is inserted in the socket.

In testimony whereof I affix my signature.
JAMES P. CASSIDY.
